TRANSPARENT SEALING DEVICE FOR
WINDOW OPENINGS

Harold A. Burnett, Wichita, Kans.

Application March 18, 1940, Serial No. 324,519

2 Claims. (Cl. 20—40)

My invention relates to an improvement in transparent sealing devices for window openings. In many buildings the windows fit so loosely in the window frames that wind and dust will readily blow between the window frame and the sash therein. In the winter time the cold wind blowing through the window opening into the house will cool the house so as to require more fuel to keep the house warm.

In the seasons of the year when the wind blows dust and dirt, the dust and dirt will be blown between the window frame and the sash therein and into the house.

In view of these facts I have provided a device that may be applied to the casings of the window that will seal the window opening so that wind, dust and dirt cannot enter the house through the window opening. Another object of my invention is to provide a device of the kind mentioned that is flexible and transparent so that the device may be rolled up for storage or transporting purposes, and when the device is in use it will not obstruct the view through the window. A still further object is to provide a device of the kind mentioned that may be easily applied to, or removed from the window casing without the use of tools. These and other objects will be more fully described as this description progresses.

Now referring to the accompanying drawings, Fig. 1 is an interior view of a window opening to which my invention is being applied.

Fig. 2 is an interior view of a window opening showing my invention in sealing position on the window casings and sill.

Fig. 3 is an interior view of a window opening to which my invention has been applied, and illustrating how the sealing device may be partially removed from the window casing so that the window sash may be raised or lowered.

Fig. 4 is a detail of the interior side of the window opening sealing device.

Fig. 5 is a detail of the exterior side of the window opening sealing device.

Fig. 6 is an enlarged sectional detail view taken along the line VI—VI in Fig. 4 and looking in the direction of the arrows.

Similar numerals of reference designate the same parts throughout the several figures of the drawings.

In the drawings is shown my improved window opening sealing device which is composed of a piece of flexible transparent material 10, the edges 11 of which are folded against themselves and permanently cemented in position so as to

form a reinforcing for the edge of the element 10. At the four corners of the element 10 is an outwardly extending tab 12 which is an integral part of the sheet 10, the object of which will be later explained.

At 13 is shown reinforcing strips which are cemented to the sheet 10 and are made of the same material as the sheet 10. On the back side of the sheet 10 and around the outer edges is an adhesive material 14. Attention is called to the fact that this adhesive material does not extend over the outer ends of the tabs 12.

The adhesive material 14 is a gum-like adhesive which may be stuck to an object and removed therefrom numerous times before its adhesive quality is gone.

This device being flexible, may be placed over anything on the window casings in the way of mouldings or other irregular shapes and still be made to tightly fit the window casing for the purpose of the invention, the device being flexible permits it to be rolled up for storage or stock housing in a store.

It will be understood that the reinforcements 13 may or may not be used, depending on the size of the piece of material 10.

Most window casings are three or more inches wide, and since the sealing device is to be stuck on the window casings, the device may be made in multiples of approximately four inches in width, such as 20 inches, 24 inches, 28 inches, 32 inches, etc., thereby making it possible for a store to carry a comparatively small stock of the window opening sealing devices and still have a full range of sizes that will take care of almost any window opening that is found in the ordinary house.

These same conditions are true in regard to the length of the device as well as the width.

Since the method of applying this device is sticking it on the opening frame, it is obvious that a device similar to this except in size could be stuck on the frame of a window or windshield in an automobile or in such places as windows in railroad passenger cars, and the like, which would provide an air space between the glass in the opening and my improved sealing device, thereby eliminating the frosting up of the glass as is common in automobiles in cold weather as will readily be understood.

Now to apply my window sealing device, the top edge 11a is stuck to the head casing 15 of the window opening. By placing the top edge of the sheet 10 in proper position as shown in Fig. 1, and pressing the edge 11a with the fingers

so that the gum adhesive 14 will stick to the casing 15 and form an air tight joint between the casing 15 and the edge 11a of the transparent sheet 10.

The head or top edge 11a of the sheet 10, being thus attached to the head casing 15, the side edges 11b of the sheet 10 are then pressed against the side casings 15a so that the side edges of the sheet 10 are stuck to the casings 15a, so as to form an air tight joint between the sides 11b of the sheet 10 and the casings 15a, and the lower end of the sheet 10 being rolled as at 10x may now be unrolled so that the lower edge 11c of the sheet 10 will rest on the upper surface of the window sill 16, whereupon the edge 11c may be pressed with the fingers so it will adhere to the window sill 16, whereupon the entire window opening has been sealed so that wind, dust or dirt cannot blow through the window opening into the room because it is stopped by the sheet 10, which has formed an air tight seal around the window opening.

Now there may be a time when it would be desirable to open a window for any one of any number of reasons, therefore the sealing device must be removed from the window casing so that the window may be opened. This may be done by taking hold of the lower tabs 12 and lifting them gently, whereupon the lower edge 11c of the sheet 10 may be pulled from the window sill 16 and a portion of the side edges 11b may be pulled from the window casings 15a and the element 10 folded rearwardly and the lower edge 11c raised

to the point 17, where the outer corners of the edge 11c are pressed against the outside edges of the sheet 10 so that the adhesive material on the edges will hold the sheet 10 in the folded position as shown in Fig. 3, then the window sash 18 may be raised or lowered without any interference with the sealing sheet 10.

Such modifications may be employed as lie within the scope of the appended claims without departing from the spirit and intention of the invention.

Now having fully described my invention I claim:

1. In a transparent sealing device for window openings; the combination of a flexible transparent piece of material, the edges of said material being turned against the main body of the material and cemented thereto as a reinforcing for the edges of the piece of material, the corners of the piece of material projecting beyond the main body of the piece to form tabs by which the piece of material may be handled, and the edge portions of the piece of material having an adhesive thereon to provide an air tight means of attaching the piece of material to a window casing as shown and described.

2. In a transparent sealing device for window openings, the combination as defined in claim 1, and strips of flexible transparent material cemented to the inner portions of the main body of the piece of material as a reinforcing therefor as shown.

HAROLD A. BURNETT.
